UNITED STATES PATENT OFFICE.

CHARLES A. HORNBURG, OF WACO, TEXAS.

DESIGN FOR A TIRE-PLACER.

57,654.

Specification for Design.

Patented Apr. 26, 1921.

Application filed February 13, 1920. Serial No. 358,401. Term of patent 3½ years.

To all whom it may concern:

Be it known that I, CHARLES A. HORN-
BURG, a citizen of the United States, resid-
ing at Waco, in the county of McLennan
and State of Texas, have invented a new,
original, and ornamental Design for Tire-
Placers, of which the following is a specifi-
cation, reference being had to the accom-
panying drawing, forming part thereof.

Figure 1 is a side elevation of a tire
placer, showing my new design.

Fig. 2 is an end elevation thereof.

I claim:

The ornamental design for a tire placer,
as shown.

C. A. HORNBURG.
